S. C. EPPENSTEIN

ADJUSTABLE BRACELET

Filed June 9, 1927

Inventor:
Sidney C. Eppenstein
By *____* *____*
____

UNITED STATES PATENT OFFICE.

SIDNEY C. EPPENSTEIN, OF ELGIN, ILLINOIS, ASSIGNOR TO ILLINOIS WATCH CASE COMPANY, OF ELGIN, ILLINOIS, A CORPORATION OF ILLINOIS.

ADJUSTABLE BRACELET.

Application filed June 9, 1927. Serial No. 197,659.

This invention relates to a bracelet of the adjustable type designed particularly for use with a watch which is to be worn upon the wrist.

5 It is an object of my invention to devise for this purpose a bracelet which will be simple, inexpensive, durable, and easily adjustable, and also to utilize in such a bracelet the minimum number of parts. It is also desired that the bracelet should be comfortable for wear, and be attractive in appearance, inasmuch as it is exposed to view much of the time. These objects and purposes have been realized by the present invention of 15 which a suggestive embodiment is illustrated in the accompanying drawing in the manner following:

Figure 1 is a view in perspective of the bracelet with an associated watch; 20 Fig. 2 is an enlarged longitudinal section taken centrally through the adjustable connection between the bracelet ends;

Fig. 3 is a view in elevation looking toward the rear or inner side of the coupling 25 which is adjustably secured to one bracelet end;

Fig. 4 is a fragmentary view looking toward the inner side of the opposite bracelet end whereon is provided a catch; 30 Fig. 5 is a similar view looking toward the outer side of the bracelet end whereon the catch is provided; and

Fig. 6 is an enlarged detail in section taken on line 6-6 of Fig. 3.

35 The present bracelet is formed of companion straps A and B each having one end 7 looped around a pin 8 which is bracketed to a watch C.

Means are provided for adjustably connecting the free ends of the bracelet straps. As shown, this comprises a coupling D having a curved back 10 with flanges 11 and 12 extended laterally at its upper and lower edges respectively, there being at one end a 45 wall 14 of lesser width connecting these flanges, as indicated best in Fig. 2. A series of aligned holes 15 are provided in two flanges for the reception of trunnions 16 extending oppositely from a sleeve 17 where- 50 in is a compression spring 18 for normally projecting these trunnions to an outermost position. The free end of strap A is shown as looped at 19 around the sleeve to establish connection therewith. By pushing in 55 the trunnions 16, the sleeve may be shifted

lengthwise of the coupling for locking within any selected of the holes 15.

Associated with the coupling is a closure plate 20 provided at one end with a pair of ears 21 which lie inwardly of the flanges 11 and 12 for pivotal connection therewith with the aid of pins 22. This closure plate is curved in conformity with the back plate 10 of the coupling and is adapted to be held by a snap connection between the two flanges 11 and 12. When so disposed a slight space remains adjacent the end wall 14 for the extension therethrough of the strap A.

The coupling is provided with a second wall 23 at the end thereof which is opposite to the wall 14. Formed in the end wall 23 is a slot 24 for receiving a spring catch 25 which is provided on the end of the strap B. This catch, as shown, is in the form of a tongue having a reversely bent portion whereon is provided a head 26 adapted to butt up against the end wall 23 when the catch is fully entered in the slot 24. Adjacent the head the tongue is provided with a groove 27 for receiving the adjacent edge of the wall 23 whereby to hold the catch in place. It is only by pressing in the tongue 25 in opposition to the tension of the material forming the catch that the latter may be disconnected from the coupling.

The operation of the present connection is already apparent from the foregoing description. The bracelet ends may be connected adjustably by first shifting the position of the coupling. This is an operation which seldom requires performance. Thereafter, the securement of the strap B to the coupling by means of the spring catch 25 is an easy matter. All the parts entering into the present adjustable connection are disposed upon the under wrist side where they are relatively obscured from view. On account of their small size and light weight, the bracelet is rendered comfortable for wear.

I claim:

1. In combination with a pair of strap ends, a coupling member comprising a plate having spaced flanges each formed with a plurality of aligned openings, said coupling having slotted end walls extending between the said flanges, one strap end extending through the slotted wall of one end of said coupling member and carrying a spring catch having oppositely extending trunnions 105

receivable within any selected pair of said openings, and a spring catch extending longitudinally with the other strap end having means for detachably engaging the slotted 5 end wall of the other end of said coupling member.

2. In combination with a pair of strap ends, a coupling member comprising a plate having spaced flanges each formed with a 10 plurality of aligned openings, a closure plate pivoted between said flanges adjacent one end of said coupling member and providing

with said first mentioned plate spaced front and rear walls, a spring catch carried by one strap end and receivable between said walls having oppositely extending trunnions engageable with any selected pair of openings in said flanges, said coupling member having a slotted end wall extending between said flanges, and a spring catch extending longitudinally with the other strap end and having means detachably engaging the slotted end wall. 15 20

SIDNEY C. EPPENSTEIN.
